AUTOMATIC FILLING NOZZLE

Henry K. Flinchbaugh, York, Pa.

Application August 10, 1937, Serial No. 158,288

8 Claims. (Cl. 226—127)

My invention relates to automatic valves and particularly to ones which are actuated to close by the submergence of the nozzle end in the liquid which has been discharged into a receptacle. Still more specifically, my invention is concerned with automatic valves for gasoline dispensing nozzles which automatically stop the flow of gasoline when the gasoline in the container being filled submerges the end of the dispensing nozzle.

This invention is a modification of my previous invention shown in my applications for United States Letters Patent filed September 16, 1936, Serial No. 101,022, and the present application is a continuation in part of the said earlier application as to all common subject-matter. Accordingly the principal object of my present invention is the provision of a simple and positively operating automatic valve for the nozzle of a gasoline dispensing unit, which can be depended upon to shut off the flow of gasoline when the end of the nozzle becomes submerged. Other objects and advantages will appear from the following detailed description of a preferred embodiment of my invention, reference being had to the accompanying drawings.

Fig. I of the drawings is a side view of a nozzle and hand valve, partially in section to show the automatic valve of my invention placed in the end of the nozzle, the automatic valve being open.

Fig. II is a side view in section of the automatic valve portion of the nozzle shown in Fig. I, with the automatic valve closed.

Fig. III is a sectional view taken on the line III—III of Fig. I.

Fig. IV is a sectional view taken on the line IV—IV of Fig. I.

Fig. V is a perspective view of the closure valve.

Fig. VI is a perspective view of the operating cylinder in which the stem of the closure valve moves.

Fig. VII is a perspective view of the spray control tube positioned at the end of the nozzle.

Fig. VIII is a perspective view of the internal nozzle positioned between the spray control tube and the operating cylinder mentioned above.

Fig. IX is a perspective view of the removable end of the operating cylinder having an automatic slide valve formed therein.

For the purposes of a detailed description of the device shown in the drawings, that device may be conveniently analyzed into an outer nozzle 1 with hand control valve 2, an automatic valve 3 having an operating cylinder 4, an internal nozzle 5 and a spray control tube 6 separated by an annular recess 7 from said internal nozzle 5.

The outer nozzle 1 and hand control valve 2 are of a conventional type and need not occupy us. The automatic valve 3 has a stem 10 formed integrally therewith and extending into the operating cylinder 4. The valve 3 is formed to cause a convergence of the fluid stream into the internal nozzle 5 in which a valve seat 11 is formed. This convergence makes the internal nozzle 5 the constriction 15.

Extending longitudinally through the valve 3 and its stem 10 is a conduit 16. The lower end of the conduit 16 is enlarged to receive in a press fit an adjustment element 17. This adjustment element 17 regulates the sensitivity of the valve and this adjustment is effected by moving the element 17 in or out. The farther the element 17 projects, the greater impediment it is to the fluid stream through the valve 3. When a greater portion of the element 17 is exposed to the pressure of the fluid stream, it is clear that the resolved force urging the element 17 downward against the pressure of the operating cylinder 4 is correspondingly increased. The angle of the fluid stream impinging on the element 17 causes this resultant downward force. Hence the sensitivity of the automatic operation of the valve 3 may be regulated by varying this resultant force through changing the degree of projection of the element 17.

On the end of the valve stem 10 is a piston 18 which works in the cylinder 4 in an obvious manner. Around the stem 10 is a coil spring 19 urging the piston 18 upward and the valve 3 open. In order to avoid the danger of fluid collection in the cylinder 4, drainage conduits 20 are provided leading into conduit 16.

At the upper end of the cylinder 4 is a head 23 in threaded engagement with the cylinder 4. This head 23 is shown in perspective in Fig. IX. In the head 23 is formed an inlet conduit 25 communicating with the cylinder 4 as will be herein-after explained. A slide valve 28 slides in conduit 29 at the bottom of which is formed a valve seat 30. From the lower part of valve 28 a stem 31 depends and extends through a conduit 32 into cylinder 4, resting on top of valve stem 10. The bottom portion of stem 31 is formed as shown in Fig. IX with a flattened end in order to avoid interfering with the free flow of liquid through conduit 16 in stem 10. The stem 31 fits very loosely in conduit 32 in order to permit the free flow of liquid therethrough when the conduit 25 is open.

The cylinder 4 is held in position by radially extending segments 34, permitting the free flow 45

of liquid through the spaces between the segments 34. At the bottom of each segment, ports 35 are formed, with conduits 36 connecting the ports 35 to the spaces between the segments 34.

5 The cylinder 4 is shown in perspective in Fig. VI. These ports 35 prevent air pockets from forming during the flow of liquid through the closure valve 3, and the interference with the proper functioning of the device caused by such air 10 pockets. Thus, there is in effect one solid stream through closure valve 3 instead of three separate ones from the spaces between segments 34.

The internal nozzle 5 is constricted by the bevel form of the valve 3 as explained above and 15 its discharge side is flared to direct the fluid stream over and without touching the annular recess 7 before hitting the wall of spray control tube 6 at points 40. The discharge side of the tube 6 is also constricted by a converging wall 20 to effect a good fluid discharge. Two air ports 38 are formed between the inside of the outer nozzle 1 and the outside of the spray control tube 6, see Fig. III. These ports 38 lead from the end of the outer nozzle 1 to the annular space 7 25 between the spray control tube 6 and the internal nozzle 5. The function of these air ports 38 is that of breathers which induce the fluid stream discharged from the internal nozzle 5 to follow its natural course over the annular recess 7 without filling up the clearance space between the stream and the spray control tube 6 at its inner end. Dotted lines in Fig. I indicate the normal course of the fluid stream from inner nozzle 5.

From the above it will be seen that the flow of 35 liquid through the outer nozzle 1 is restricted at the constricted portion of the internal nozzle 5, consequently forcing the liquid through by pressure. The lower or outer end of the internal nozzle 5 is tapered allowing the liquid to spread 40 and to that degree guiding the spread of the flow to contact the spray control tube 6 at points 40 creating an air chamber around the annular recess 7 that has ports 38 to allow the flow of liquid its natural breathing of air as it spreads. 45 As the liquid flows through the internal nozzle 5 it is also flowing through the conduit 25 into a pressure chamber 41 of the cylinder 4, out through the conduit 16 in the valve stem 10 and the valve 3, continuing through the adjustment 50 element 17 into the center of the main flow of liquid.

As the pressure increases or decreases in the outer nozzle 1 the flow of liquid through the internal nozzle 5 and through the adjustment element 17 also increases or decreases with the pressure. It is to be noted that the conduit in element 17 is of a smaller cross sectional area than that of the conduit 16 and hence this adjustment element 17 is effective as a small nozzle 60 at the end of conduit 16. Now as the flow of liquid increases through the adjustment element 17 the flow of liquid that encircles the element 17 increases, increasing the pull of the liquid exhaust of the pressure chamber 41 out through 65 the conduit 16. This creates a more uniform pressure in the pressure chamber 41, thus creating a wider range of operating pressures of the automatic shut-off nozzle than exists in the pump installations now in use.

70 The automatic shut-off takes place when the liquid in the container being filled reaches the discharge end of outer nozzle 1 closing off the air ports 38 from the atmosphere which cuts off the air that is being breathed in by the flow 75 of liquid spreading as it flows out of the internal

nozzle 5. The cutting off of this source of air in turn increases the draw or pull from the center of the flow which increases the pull on the adjustment element 17 and the valve 3 enough to move the valve down on to its seat 11. 5 This in turn allows the control valve 28 to move down to its seat 30 under pressure in the outer nozzle 1 on top of the valve 28, closing the conduit 25 and completing the automatic shut-off. To reopen valves 3 and 28, the hand control valve 2 is closed which relieves the pressure on the valves 3 and 28 and permits them to be lifted 10 from their respective seats 11 and 30 by the pressure of the spring 19 to their normal position. 15

The adjustment element 17 is held by a press fit which can be moved to extend out of the valve 3 to a variety of lengths, which counteracts the pressure of the valve spring by the flow of liquid contacting the surface of the sides of the adjustment element 17 from the angle of the flow at that point. This creates an adjustment of the sensitivity of the automatic valve by the amount of the surface of the element 17 exposed to the flow. 20

While I have described this preferred embodiment of my invention in detail, it is obvious to one skilled in the art that numerous changes might be made and such modifications are deemed to be within the spirit of the invention 30 as hereinafter claimed.

Having thus described my invention, I claim:

1. The combination of an outer nozzle, a closure valve within said nozzle, a closure valve stem, a conduit formed in said valve and valve stem, a longitudinally thereof, a pressure means urging said valve open, a closing piston attached to the end of said valve stem, an operating cylinder in which said piston operates, said cylinder having an inlet port at the supply end of said cylinder, 35 a control valve closing said inlet port when said closure valve is in the closed position, an internal nozzle into which said closure valve opens, a spray control tube positioned at the discharge end of said internal nozzle and extending to substantially the end of said outer nozzle, and an air duct leading from the end of said outer nozzle to a point between said inner nozzle and said spray control tube. 40

2. The invention of claim 1 wherein the operating cylinder is supported within said outer nozzle by radially projecting portions having discharge ports formed in the ends of said radially projecting portions, said discharge ports having conduits leading to the spaces between said radially projecting portions. 45

3. The invention of claim 1 wherein the closure valve stem has formed therein a conduit connecting said operating cylinder with the longitudinally extending conduit in said valve stem. 50

4. The invention of claim 1 wherein an adjustment member is positioned at the discharge end of said conduit formed longitudinally in said closure valve and valve stem, said adjustment member having capacity for adjustment longitudinally of said valve stem. 55

5. The invention of claim 1 wherein said internal nozzle and said spray control tube are separated from each other by an annular recess. 60

6. The invention of claim 1 wherein said control valve is of the sliding type and has a depending stem connected to the valve piston and which rests on said closure valve stem following the movement thereof. 65

7. In combination, an outer nozzle, a closure 70

valve within said nozzle, a pressure means forcing said valve open to allow fluid discharge past said valve, a closing piston within said nozzle and normally exposed to the fluid pressure in said nozzle, an exhaust duct leading through said closure valve and discharging centrally into the stream of liquid flowing past said closure valve, and a control valve for cutting off said fluid pres-

sure from said closing piston, when said closure valve is closed.

8. The invention of claim 7 wherein the exhaust duct has an adjustable projecting nozzle element attached to its lower end, the cross-sectional area of said nozzle being smaller than that of said exhaust duct. 5
